UNITED STATES PATENT OFFICE.

J HERBERT LANDES, OF NORRISTOWN, PENNSYLVANIA.

TIRE PUMP.

Application filed August 20, 1921. Serial No. 493,847.

To all whom it may concern:

Be it known that J HERBERT LANDES, a citizen of the United States, residing at Norristown, in the county of Montgomery and 5 State of Pennsylvania, has invented new and useful Improvements in Tire Pumps, of which the following is a specification.

This invention relates to pumps, and, more particularly, to a pump intended primarily for application to motor vehicles for 10 use in inflating tires.

An object of the invention is to provide a pump which is simple in construction, inexpensive to manufacture, readily applicable 15 to a vehicle, and highly efficient in operation.

Another object of the invention is to provide a pump construction which will take up but a small amount of space and, hence, may be readily placed in position within the 20 hood and adjacent the motor of practically all makes of vehicles.

A still further object of the invention is to provide an extremely simple and efficient arrangement for connecting the pump to the 25 motor and which may be actuated to throw the pump into operation without stopping the motor.

The above and other objects of a similar 30 character will become more clear from the following description of the embodiment of the invention which is shown in the accompanying drawings, in which

Fig. 1 is a side elevational view of a portion 35 of a motor showing the pump applied in position.

Fig. 2 is a front elevational view of the pump, and

Fig. 3 is a longitudinal cross section of the same.

Referring to the drawings more in detail, 40 10 indicates a bracket which supports a cylinder 11 having heads 12, 13, and enclosing a piston 14 provided with a hollow rod 15. The rod 15 extends through an opening in 45 15 the cylinder head 13 and receives the end of a rotatable shaft 16 having a bearing 17 in a depending ear 18 of the bracket. The shaft 16 is formed with reversely arranged helical 50 19 grooves terminating at each end in common curved paths 19', as indicated in Fig. 3. The piston rod 15 may be formed with a key 20 extending through a channel in the cylinder head adjacent the opening through which the rod extends in order to prevent 55 20 its rotation with the shaft 19; and in order to effect reciprocatory movement of the pis-

ton and rod, a follower 21 is secured to and extends through the rod into the helical grooves. On the opposite side of the ear 18 the shaft may have thereon a stop collar 22 60 to hold it against longitudinal movement, and is provided with means, such as the worm 23 slidably mounted upon the shaft, for clutching the shaft to a rotating part of a motor. 65

In order to throw the gear 23 into and out of operative engagement with the motor, a slide bar 24, having a longitudinally extending slot 25, is mounted upon the bracket 10 and is held in position by a boss 26 upon the 70 bracket extending through the slot 25. A locking plate 27 is secured to the boss by means of a screw 28, and has its ends extending over the slide bar to prevent upward movement of the same. One end of 75 the slide bar is formed with a depending arm 29 having a fork 30 surrounding the hub of the worm 23, and the other end has an upwardly extending handle 31 by means of which the slide bar may be operated. A 80 spring catch 32, secured to the slide bar adjacent the handle, is adapted to engage in spaced oppositely inclined grooves 33 formed in the bracket to hold the bar in either of its two extreme positions. When the slide bar 85 is moved toward the left, from the position shown in Fig. 3, the depending portion of the spring clip will be flexed in the direction of the end of the slide bar, as it engages the end of the groove, and when it reaches the 90 groove further to the left will spring downwardly into the same to hold the slide bar in position. Obviously when this movement takes place the worm 23 will be moved with the slide bar from its position shown in 95 Fig. 3.

The invention also contemplates the provision of means for preventing the inflation of a tire to too high a pressure, and to accomplish this object, in the head 12 is located a relief valve 35 which will remain 100 closed until a certain predetermined pressure, to which the valve is adjusted, is reached, whereupon the valve will open and further actuation of the pump will result 105 merely in passage of the air through the exhaust valve instead of through the delivery nozzle. The delivery nozzle 36 is shown as located upon the same fitting with the exhaust valve. An inlet valve 38 may also be 110 located in the head 12 of the cylinder.

The entire construction, above described,

is supported by means of bars 39 secured to each end of the cylinder, as by bolts 40, and to the motor, as indicated in Fig. 1. The pump should, preferably, be positioned in the front of the motor so that the worm 23 may be thrown into engagement with a spiral gear 41 formed, preferably, integral with the driving pulley 42 for the fan belt which is generally located upon the crank shaft 43. Obviously, the invention is not limited to the specific construction described, since the disclosure and description is merely illustrative and in no sense restrictive of the invention. Such modifications may be made without departing from the invention, as come within the scope of the following claim and as are equivalent to the structure set forth.

I claim:

20 A tire pump comprising a bracket, a cyl-

inder mounted on said bracket, a piston in said cylinder, a hollow rod secured to the piston, a rotatable shaft having a bearing in said bracket and projecting into said rod, said shaft having reversely arranged helical grooves thereon terminating in common curved paths, a follower secured to the rod and projecting into said grooves, a worm gear slidably secured to said shaft, a crank shaft positioned at substantially right angles to said rotatable shaft, a member longitudinally slidable on said bracket for throwing said worm gear into and out of engagement with said spiral gear, and a spring catch for holding said member in selected position.

In testimony whereof I have hereunto set my hand.

J HERBERT LANDES.
